DISPLAY CARD

Jay C. Nofziger, Los Angeles, Calif.

Application August 6, 1940, Serial No. 351,581

5 Claims. (Cl. 40—124.1)

This invention relates to display cards.

The general object of the invention is to provide a display card including novel supporting means.

Another object of the invention is to provide a display card including novel integral means including interlocking side flaps which provide a rigid support.

Another object of the invention is to provide a display card including a novel compartment display portion.

Another object of the invention is to provide a windowed display card having a novel lock member.

A further object of the invention is to provide a novel display card in the general form of a star.

Other objects and advantages of the invention will be apparent from the following description taken in connection with the accompanying drawings, wherein:

Fig. 1 is a plan view of a display card embodying the features of my invention;

Fig. 2 is a front view of the display card in assembled position;

Fig. 3 is a side elevation of an assembled display card;

Fig. 4 is a plan view of a blank forming a modified display member;

Fig. 5 is a front view of the modified display member;

Fig. 6 is a side elevation with parts broken away showing the modified member;

Fig. 6A is a fragmentary view similar to Fig. 6 on an enlarged scale;

Fig. 7 is a plan view of a further modified display member;

Fig. 8 is a front view or an enlarged scale of the further modification; and

Fig. 9 is a side elevation of the further modification.

Referring to the drawings by reference characters I have shown my invention as embodied in a display panel which is indicated generally at 10. As shown the panel includes a body portion 11 having a score line 12 adjacent each side of the panel, a score line 13 adjacent the top of the panel and a score line 14 adjacent the bottom of the panel. The score lines 12 are parallel to each other and the score lines 13 and 14 are likewise parallel and the four score lines, in general, define a rectangle.

Each of the score lines 12 and 13 terminates in an arcuate slit 15 with the slits outwardly directed and each slit merges into a straight slit

16 which extends to the outer edge of the body portion as clearly shown.

The score line 14 terminates in an outwardly directed straight slit 17 which merges into a second straight slit 18 which continues to the outer edge of the body.

The various slits define side flaps 19, a top flap 20 and a bottom flap 21. Adjacent the juncture of the side flaps 19 and the top flap 20 the flaps 19 are provided with notches 22 which are adapted to engage notches 23 in the top flap. The side flaps 19 are also provided with lower notches 24 which are adapted to engage notches 25 in the bottom flap 21. In use the flaps 19, 20, and 21 are folded and the notches are interlocked as shown in Fig. 3 to form a supporting frame about the body 11 of the panel. The lower edges 26 of the side flap 19 are bevelled in such fashion that the panel body 11 is inclined at the desired angle as shown in Fig. 3.

In Figs. 4, 5, and 6 I show a modification of my invention wherein the display panel includes a receptacle. In the modification the body 30 is provided with score lines 31 along each side, an upper score line 32, and a lower score line 33. Each score line terminates in an arcuate outwardly directed slit 34 and each of the slits 34 intersects a straight slit 35 so that a pair of side flaps 36, a top flap 37 and a bottom flap 38 are provided. The flaps are provided with slots 37' at each end which in the assembled construction interlock to hold the flaps at right angles to the body 30.

The body 30 is provided within the area defined by the score lines 31, 32, and 33, a viewing aperture 39, with side score lines 39, and with a bottom score line 40 which define side flaps 41 and a bottom flap 42 thus defining portions of the aperture 39. These flaps are separated from the body by curved slits 43 at the top thereof and by straight slits 44 at the bottom thereof so that the flaps 41, 41, and 42 may be folded perpendicular to the body 30. Each side flap 41 includes a plurality of tongues 45 which have upwardly directed ears 46 thereon and the lower flap 42 includes short tongues 47.

Integral with the lower flap 38 I show a back member 48 which is connected to the flap 38 by a score line 49. The score line 49 at each end terminates in outwardly directed slits 49'. The flaps 41 and 42 are adapted to be folded perpendicular to the body 30 and the back 48 is then folded along the score line 49 until it is parallel with the body 30 and is in alignment with the flaps 41 and 42. The back 48 includes

slots 50 along the side and intermediate slots 51. The slots 51 receive the tongues 47 and the slots 50 receive the tongues 45.

In construction the flaps 36, 37, and 38 are preferably first folded to position and their interlocking members 37' are engaged. The flaps 41 and 42 are then bent at right angles to the body and the back 48 is moved parallel to the body about the crease line 49. The slots 50 are aligned with the tongues 45 and are passed over these tongues as shown in the dotted line position in Fig. 6A after which the back is shifted downwardly to the full line position in Fig. 6A and the parts are thus locked in assembled position.

In Figs. 7, 8, and 9 I show a further modification of my invention wherein the body 60 is provided with top side score lines 61 and an intermediate inverted substantially V-shaped slit 62 to provide a top flap 63. At each side I provide a side flap 64 connected to the body by a score line 65 and severed from the body along an inclined slit 66 providing a tongue 67.

Each tongue 67 has a slot 68 adapted to engage in a slot 69 on the upper edge of the top flap 63 when the parts are in operative position.

The body further includes a bottom flap 70 connected to the body by a score line 71 and having inclined slits 72 at each side thereof. The slits 72 define bottom tongues 73 which have slots 74 therein. When the flap 70 is bent to operative position as shown in Figs. 8 and 9 each slot 74 is engaged in a companion slot 75 on the adjacent side flap 64 to hold the parts assembled.

As in the previously described types, the lower edge 76 of the side flap 64 engages a support and serves to hold the display member erect while the lower outer edges of the body also serve to support the device.

It will be noted that the body disclosed in Fig. 9 is of general star shape and that all of the devices provide neat, attractive display panels which can be readily manufactured and assembled.

Having thus described my invention, I claim:

1. In a display panel, a body having a score line adjacent to the top, bottom and each side thereof to define edge portions, the opposed score lines being parallel, said body having an outwardly directed slit at each end of the score lines, a straight slit extending from the end of each of said outwardly directed slits and being arranged parallel to the adjacent score line, each edge portion being foldable along its score line to define a flap and each outwardly directed slit and its associated straight slit defining a tongue, said tongues being on the flaps, said tongues at each corner of the body overlapping and being disposed in planes arranged at right angles to each other, the overlapping tongues including interlocking slots.

2. In a display panel, a body having a score line adjacent to the top, bottom and each side thereof to define edge portions, the opposed score lines being parallel, said body having an arcuate slit at each end of the side and the top score lines, said arcuate slits being outwardly directed, said body having an outwardly directed straight slit at each end of the bottom score line, a straight slit extending from the end of each of said outwardly directed slits and being arranged

parallel to the adjacent score line, each edge portion being foldable along its score line to define a flap and each outwardly directed slit and its associated straight slit defining a tongue said tongues being on the flaps, said tongues at each corner of the body overlapping and being disposed in planes arranged at right angles to each other, the overlapping tongues including interlocking slots, the lower ends of each side portion 10 being bevelled to form a support.

3. In a display panel, a body having a score line adjacent to the bottom thereof to define an edge portion, said edge portion being foldable along its score line to define an outer bottom flap, said body having a viewing aperture, an inner flap at each side of the aperture, said inner flaps being integral with the body and having tongues thereon, said body bottom outer flap having a back member connected thereto by a score line, said back member being foldable parallel to the body and having slots therein receiving the tongues on said inner flaps.

4. In a display panel, a body having a score line adjacent to the top, bottom and each side thereof to define edge portions, said body having a slit at each end of the score lines, each edge portion being foldable along its score line to define outer side flaps and an outer bottom flap, each slit defining a tongue, said tongues at each corner of the body overlapping and being secured together, said body having a viewing aperture, an inner flap at each side of the aperture and an inner flap at the bottom of the aperture, said inner flaps being integral with the body and having tongues thereon, the tongues on the side flaps having upwardly directed ears, said body bottom outer flap having a back member connected thereto by a score line, said back member being foldable parallel to the body and having slots therein receiving the tongues on said inner flaps.

5. In a display panel, a body having a score line adjacent to the top, bottom and each side thereof to define edge portions, the opposed score lines being substantially parallel, said body having an arcuate slit at each end of each score line, said arcuate slits being outwardly directed, a straight slit extending outwardly from both ends of each slit, each side edge portion and the top edge portion being foldable along its score line to define an outer flap, the bottom edge portion being foldable to provide an outer bottom flap each outwardly directed slit and its associated straight slit defining a tongue, said tongues at each corner of the body overlapping and being disposed in planes arranged substantially at right angles to each other, the overlapping tongues including interlocking slots, the lower ends of each side portion being bevelled to form a support, said body having a viewing aperture, an inner flap at each side of the aperture and an inner flap at the bottom of the aperture, said inner flaps being integral with the body and having tongues thereon, the tongues on the side inner flaps having upwardly directed ears, said body bottom outer flap having a back member connected thereto by a score line, said back member being foldable parallel to the body and having slots therein receiving the tongues on said inner flaps.

JAY C. NOFZIGER.
